(57) **CLAIM**

The ornamental design for a machine for making ice-cream, as shown and described.

DESCRIPTION

FIG. 1 is a front perspective view of a machine for making ice-cream, according to the invention;

FIG. 2 is a front view thereof;

FIG. 3 is a right side view thereof;

FIG. 4 is a left side view thereof;

FIG. 5 is a rear view thereof;

FIG. 6 is a top view thereof;

FIG. 7 is a bottom view thereof;

FIG. 8 is a front perspective view of a machine for making ice-cream, according to the invention;

FIG. 9 is a front view thereof;

FIG. 10 is a right side view thereof;

FIG. 11 is a left side view thereof;

FIG. 12 is a rear view thereof;

FIG. 13 is a top view thereof;

FIG. 14 is a bottom view thereof;

FIG. 15 is a front perspective view of a machine for making ice-cream, according to the invention;

FIG. 16 is a front view thereof;

FIG. 17 is a right side view thereof;

FIG. 18 is a left side view thereof;

FIG. 19 is a rear view thereof;

FIG. 20 is a top view thereof; and,

FIG. 21 is a bottom view thereof.

Any broken lines in the figures illustrate portions of the machine for making ice-cream that form no part of the claimed design.

1 Claim, 21 Drawing Sheets
